CONTAINER KEY

David Hunt Wheaton, Winnetka, Ill., assignor to McCann-Erickson Incorporated, New York, N.Y., a corporation of Delaware

Application April 23, 1956, Serial No. 580,071

2 Claims. (Cl. 220—52)

This invention relates to keys for the opening of containers and to combinations of such keys with containers, and is particularly concerned with such keys and combinations which incorporate a removable identifiable means, or premium coupon.

In the retail marketing of commodities in containers there is an ever increasing effort to provide some sort of coupon or the like, which can be detached and used for obtaining some sort of premium, for participating in some contest, or for entering into some other sales promotional plan. Where the containers carry some sort of wrapping that is removable, the coupon can be readily formed as a part of the wrapping, and wrappings for this purpose are readily applicable to the ordinary cylindrical cans containing such as food products, which are opened by using one of the conventional can openers. There are also various other schemes employed for carrying coupons in conjunction with such cans ranging from using a carrying strip on the outside to placing the coupon inside when that is not harmful to the contents.

In the case of cans openable by means of a key actuating a tear strip, many of the schemes used in other fields are not workable. Furthermore, the cans involved are often of such small size that the application of additional elements is not practical or economic.

This invention is concerned with overcoming the drawbacks in this field and takes a big step forward. It does these things by utilizing and modifying means already present on the cans to perform the additional function of providing an identifiable means, or coupon, without any material increase in structure or cost, particularly without any addition in labor cost. All this is done while solving the problem in an interesting, attractive manner appealable to the customer. Principally, it is effected by modifying the key blank carried by the can for use in actuating the tear strip so that a portion of the key blank is removable for use as a coupon.

It is, accordingly, an object of this invention to provide for the carrying of identifiable means, or coupons, on containers which are openable by means of a tear strip.

Another object is to provide such identifiable means, or coupon, which is carried by the key blank secured to the container.

Still another object is to provide such means which can be readily removed from both the container and the key for retention and use as evidence of purchase of the container carrying it.

A more detailed object is to form the identifiable means, or coupon, as an integral part of the key blank for securing to the container.

Further and more detailed objects will in part be obvious and in part be pointed out as the description of the invention taken in conjunction with the accompanying drawing proceeds.

In that drawing, in which the presently preferred and modified embodiments of the invention are illustrated:

Fig. 1 is a bottom plan view of a can of the type normally openable by means of a tear strip showing the

2

key blank of the invention secured in place on that bottom.

Fig. 2 is an elevation of the key blank after removal from the container, but prior to the removal of the identifiable means, or coupon, from the blank.

Fig. 3 is an exploded view similar to Fig. 2 showing the coupon removed.

Fig. 4 is a view similar to Fig. 1 of a somewhat modified form of the invention.

Fig. 5 is a perspective view of the key blank of Fig. 4 removed from the container but with the coupon still attached thereto.

Fig. 6 is an exploded view of the key blank of Fig. 5 with the coupon and key separated.

Fig. 7 is an enlarged plan view of the coupon of Figs. 5 and 6; and

Fig. 8 is a similar view of a further modified form of coupon.

As indicated heretofore and in the description to follow, the identifiable means carried by and for removal from the key blank is more conveniently referred to by the term "coupon." That term will accordingly be employed in the interests of simplicity of description, but without in any means limiting the generality of use for the elements in question.

In Fig. 1, the can 1, selected for the purpose of illustration, is of the type normally referred to as a sardine can, though it is to be understood that the invention is applicable to any cans carrying keys for use in the opening of a can by means of a tear strip.

The can 1 has a bottom 2 to which the key blank generally indicated at 3 is secured. The key blank 3 is here shown as a wire member having a handle portion 4, a shank 5, and a flattened and widened key section 6 slotted at 7 for the reception of a tear strip, as is well known in this art. These parts make up the key when they are freed from the rest of the blank.

The complete key blank of the invention has two additional sections 8 and 9, preferably formed integrally with the main key stem. The portion 8 forms the coupon of the invention, while the securing portions 9 is soldered, or otherwise secured, to the bottom 2 of the can for carrying the key blank with the can while the sections are still joined.

The section 8 is joined to the section 6 by a frangible section 10 of reduced cross section, while the portions 8 and 9 are joined together by another reduced frangible portion 11. Preferably the portion 10 is less frangible than the portion 11, since the aim is to remove the key itself and the section 8 while both are still secured together. This is done by raising the key and breaking the section 8 away from the section 9 at the portion 11. Then the key can be taken in hand and the coupon 8 can be readily removed therefrom by breaking it off at the portion 10.

The key blank removed from the container, with the frangible portion 10 unbroken and the coupon 8 still carried by the section 6, is illustrated in Fig. 2. In Fig. 3 these sections are shown as separated with the key standing alone, ready for use in opening the container, and with the coupon 8 removed for retention and use in the obtaining of a premium, entry into a contest, or whatever the merchandising arrangement may be.

It is, of course, to be understood that the frangible portions could be so formed that the key could be broken off at the section 10, as the first step and then the coupon 8 could be broken away from the secured portion 9 at the section 11. However, it is simpler and preferable to remove and separate the key and coupon in the manner first described. In any event, the coupon 8 should be removed from the key before the tear strip is wound up, for otherwise the tear strip might overlap it and prevent its removal.

In the modification of Figs. 4, 5 and 6, the key blank has portions 4, 5, and 6, the slot 7 and the secured portion 9, the same as in the Fig. 1 form. Here, however, the coupon section 18, in the position of the sections 8 of Fig. 1, is thinned out and enlarged so as to be more readily distinguishable as a separate element and to more readily carry numbers or other indicia, as indicated at 19. This thinning out and enlarging of the section 18 can be effected in the course of the die operation which flattens the portions 6 and 9 from the normal round contour of the wire at 5 and punches the slots 7. Again, by suitable die action, frangible sections 20 and 21 are so formed that the key blank will break off at the section 21, leaving the coupon 18 joined with the key itself, as illustrated in Fig. 5. Then the coupon 18 can be readily grasped and broken away from the remainder of the key as shown in Fig. 6.

A slightly different form of coupon is shown at 28 in Fig. 8. Here the coupon is of substantially rectangular form, occupying a little less area than the coupon 18 of Figs. 5-7. It would, however, be made in the same way by a coining of the wire and would have frangible sections at its ends 29 and 30. Like the coupon 18, it would, of course, be considerably thinner than the coupon 8, since the latter would be a normal extension of the flattened portion 6 of the key stock. The coupon 28 is also readily adaptable for the application of indicia as indicated at 31.

It is, of course, to be understood that certain changes may be made in the above product and different embodiments of the invention could be made without departing from the scope thereof. It is, accordingly, in-

tended that all matter contained in the above description, or shown in the accompanying drawing, shall be interpreted as illustrative and not in a limiting sense.

Having described my invention, what I claim as new and desire to secure by Letters Patent is:

- 5 1. A metal key for use in actuating a tear strip comprising, a body portion including a handle portion, a shank portion extending from said handle portion and a flattened slotted portion extending from said shank portion, a plurality of flattened removable elements integral with said body portion and extending outwardly from said slotted portion, one of said removable elements being integrally connected to said body portion and the next adjacent one of said removable elements being integrally connected to said one element, said integral connections for said removable elements being reduced in cross section to render them weakened and readily breakable, said one of said removable elements being formed with indicia thereon.
- 10 2. A metal key as in claim 1 and including said integral connection between said first and next adjacent elements being weaker and more readily breakable than said integral connection between said body and said one removable element.
- 15 25
